REFLECTOR

Wallace A. Stanley, Bloomfield Hills, Mich., assignor to Reflex Corporation of America, Troy, Mich., a corporation of Michigan

Filed July 26, 1965, Ser. No. 86,292

Term of patent 14 years

(Cl. D72—1)

FIG. 1 is a perspective view of a reflector embodying my new design.

FIG. 2 is a plan view of the same.

FIG. 3 is a side elevational view of the same.

FIG. 4 is a fragmentary front elevational view of a portion of the reflector.

FIG. 5 is a fragmentary rear elevational view of a portion of the reflector.

FIG. 6 is a fragmentary sectional view taken along the line 6—6 in FIG. 2.

FIG. 7 is a perspective view of a modified form of the reflector.

FIG. 8 is a perspective view of a further modified form of the reflector.

I claim:

The ornamental design for a reflector, substantially as shown and described.
